UNITED STATES PATENT OFFICE.

THEODORE BENDER, OF PROVIDENCE, RHODE ISLAND, ASSIGNOR TO ROGER WILLIAMS SILVER COMPANY, OF PROVIDENCE, RHODE ISLAND, A CORPORATION OF RHODE ISLAND.

DESIGN FOR A VEGETABLE-DISH.

41,766.

Specification for Design.

Patented Sept. 12, 1911.

Application filed May 26, 1911. Serial No. 629,752. Term of patent 14 years.

To all whom it may concern:

Be it known that I, THEODORE BENDER, a citizen of the United States, residing at Providence, in the county of Providence and State of Rhode Island, have invented a new, original, and ornamental Design for Vegetable-Dishes, of which the following is a specification, reference being had to the accompanying drawing, forming part thereof.

The figure is a perspective view of a vegetable dish, showing my new design.

I claim:

The ornamental design for a vegetable dish, as shown.

THEODORE BENDER.
